PACKAGE FOR DRY GOODS, AND METHOD
AND APPARATUS FOR MAKING THE
SAME

Alfred J. Brooks, Jamaica Plain, Mass.,

Application April 29, 1935, Serial No. 18,718

6 Claims. (Cl. 226—18)

This invention relates to packages and particularly to a type of package for use by laundries, dry cleaners and similar establishments, though it will be understood as the description proceeds 5 that this type of package is eminently adapted for use by department stores and dress shops.

A primary object of the invention is to provide a packaging combination of the foregoing type which will be simpler in construction, more 10 easily assembled and relatively less expensive than the ordinary type of cardboard container now in general use for the same or similar purposes.

Another object is to transform the conventional 15 type of paper bag into a rigid container for dry goods and other materials that must be protected from crushing.

Another object is to provide a relatively simple method for wrapping or packaging dry goods and 20 analogous materials.

Still another object is to provide a method of the foregoing type which is exceedingly flexible in that it is suitable for wrapping or packaging various quantities of different sized articles and 25 for producing packages of different shapes and sizes.

The essence of the invention which renders the foregoing objects possible of accomplishment resides in providing two end blanks and a paper 30 tube or bag, the two end blanks being adapted to be disposed in spaced relation to receive between them the goods to be packaged and then to be inserted with the goods into the tube or bag, the tube or bag being finally closed and 35 sealed to complete the package.

A further object is to provide a device of relatively simple construction for facilitating the operations which constitute the steps of the foregoing method.

Another object is to provide a device of the foregoing type which is suitable for wrapping or packaging various quantities of different sized articles and for producing packages of different shapes and sizes.

The essence of the invention which renders the foregoing two objects possible of accomplishment resides in providing a U-shaped trough for supporting in spaced relation the two end blanks which are to form component parts of the pack- 45 aging combination. Positive means may be provided for holding the blanks against unintentional displacement at any desired relative positions within the limits of the trough.

Referring briefly to the drawings, Figure 1 is a perspective view illustrating the

first step in my process; namely, positioning the end blanks on a flat surface to receive between them the articles to be wrapped or packaged;

Figure 2 is a similar view illustrating the second step in the process; namely, placing the articles between the end blanks;

Figure 3 is a similar view illustrating the third step in the process; namely, slipping the wrapper or bag over the end blanks from one end.

Figure 4 is a similar view, partly broken away, 10 illustrating a subsequent step in the process; namely, closing and sealing the package;

Figure 5 is a perspective view, partly broken away, of a preferred form of device by means of which I may carry out the steps of the process; 15 the end blanks being shown in position to receive between them the articles to be wrapped or packaged; and

Figure 6 is a cross-section taken along line 20 6—6 of Figure 5 and looking in the direction of the arrows, the bag being shown as it is slipped over the end blanks in the third step of the process.

Referring to the drawings in greater detail and more particularly to Figures 1 to 4 thereof, the reference letters A and B represent the two end blanks and the letter C designates the paper bag or tube which form essential parts of the novel packaging combination. Each of the end blanks is U-shaped in cross-section, the legs being denoted by 1 and 2 and the yoke by 3. The end blanks may be formed in any suitable manner from a material having the requisite rigidity or stiffness to effectively cooperate with the bag C to form the self-sustaining package of Figure 4. 25 The end blanks may advantageously be made from strips of double-faced corrugated paper-board, scored and bent along the lines 4 and 5. The corrugations are shown as being parallel to the length of the blanks, but they may be disposed at right angles thereto. A reinforcing strip (not shown) may be applied to the corners, 30 if thought necessary or desirable.

The element C of my packaging combination is 35 illustrated as being a paper bag, having the closed end 6 and the open end 7, though it will be understood that a paper tube open at both ends is well adapted for use in my invention. I prefer to utilize a bag of the so-called "automatic" or "self-opening" type, as its use greatly simplifies the setting up of the container. Furthermore, this type of bag gives a smoother back to the package and forms a relatively neater package than the so-called "square" or "old-fashioned" type of bag. However, I do not preclude 40

45 50 55

the use of any other type of bag from the spirit of my invention. The bag may be made of paper of any desired grade, weight, thickness or ply, and may be printed.

Having described the essential elements of the combination embodying the invention, I shall now describe the manner in which the elements are assembled and utilized. The two end blanks A and B are placed on edge on a flat surface such as a table top T, the corresponding legs being in alignment and extending toward each other, the distance between the yokes being somewhat greater than the length of the desired package. This step is illustrated in Figure 1. Then as indicated in Figure 2 the articles S to be wrapped or packaged are inserted between the blanks. The articles are shown as being shirts, but any other dry goods may be wrapped in the same manner. The next step (see Figure 3) consists in slipping the opened bag or tube C over the blanks from one end. The articles and the blanks may be readily inserted into the bag by applying pressure against the blank A. The final steps or operations are illustrated in Figure 4. The bag is stood on its closed end; the assembled blanks and articles are pushed toward the bottom of the bag to seat the lower end blank B in the very bottom of the bag; the open end 7 of the bag is folded over the upper end blank A and sealed in any suitable or well known manner. As shown in Figure 4, I prefer to employ a gummed tape 8 for the purpose, though I may use a string and button arrangement or a gummed surface suitably applied to the edge of the bag during its manufacture. A laundry slip may be attached to the sealed end of the package in any suitable manner.

From the foregoing description it will be readily understood that I have provided a container or packaging combination which is much easier to set up than the ordinary type of folding box. It is less expensive than a folding or rigid box of similar cubical capacity. The parts can be stored flat, hence requiring less room than boxes for storage, especially since the two end blanks are of exactly similar construction. The assembled package is stronger than a box at the corners where the packaged articles are most likely to be subjected to crushing. Furthermore, the air entrapped with the sealed contents forms a cushion so that the paper bag cannot be easily punctured. Hence, it is not at all necessary to use stiffening or reenforcing means at the top and bottom of the bag and the package can be handled in exactly the same manner as a box. A large number of packages may be stacked one above the other without crushing the articles in the lower packages. Another advantage of the new package is that it can be unpacked with great ease, and the bag and the end blanks can be very easily disposed of after they have served their intended purpose.

It will be understood from the foregoing description that the dimensions of the end blanks and of the bag or tube may be varied within wide limits depending upon the size and shape of the desired package. The length of the bag may be varied by varying the distance between the end blanks; its width may be varied by varying the length of the yoke 3 (i. e. the distance between the legs of the blank); and its breadth may be varied by varying the width of the end blank. To obtain the most satisfactory results the bag should be about $\frac{1}{4}$ " wider than that of the end blank.

As has been pointed out the steps or operations of my new process may be carried out on a flat surface such as a table without the use of any

mechanical devices. The operations may be carried out very expeditiously by means of the device illustrated in Figures 5 and 6.

Referring to these figures, the device consists essentially of a U-shaped trough 10, its side walls being indicated by 11 and 12 and its bottom or floor by 13. The trough may be of any suitable material such as metal and its floor or bottom 13 may terminate at its forward end in a forwardly extending lip 14 to serve a purpose to be herein-after pointed out. Secured to the side walls 11 and 12 near their forward ends in any suitable manner as by soldering are the two narrow blades 15 and 16, the sharp edges of which point to the forward end of the trough and terminate short of the forward ends of the side walls. The blades are preferably disposed at a slight downward angle and are spaced a short distance from the walls, all for reasons to be hereinafter pointed out.

The reference numerals 17 and 18 designate two end stops mounted near the rear end of the trough. Each stop consists of a narrow blank of metal bent at right angles to form the two arms 19 and 20. The horizontal arm 20 is provided with the elongated slot 21 which receives the screw 22 which serves to adjustably secure the stop to the bottom of the trough. The vertical arms 19 of the two stops serve as guides for the positioning of one of the end blanks.

The trough 10 is preferably mounted on a base or support 23 to which it may be secured by means of the screws 24. The base 23 which may be of wood or other suitable material has a rectangular raised portion 25 and a lower portion 26, the trough 10 being secured at its rear end to the raised portion. There is thus provided a slot 27 between the major portion of the trough and the base. This slot serves a purpose to be hereinafter brought out.

To use the device the end stops 17 and 18 are properly adjusted for the size package to be made and the end blank A is placed against the stops as indicated. Then the end blank B is placed in position. A suitable way of positioning this blank is to press the free end of each leg against the corresponding blade 15 or 16, so that the blade enters a corrugation. Since the blades are inclined downwardly, the lower edge of the legs will ride up and be raised above the floor of the trough. This prevents the lower corners from jamming against the trough and facilitates the subsequent step of inserting the blanks and the articles into the bag. The blades are of resilient material and as has been previously stated are spaced from the walls to which they are attached. Hence they firmly clamp the legs of the end blanks against the walls. If desired spring clips with or without sharp edges may be substituted for the blades, in which case the entire thickness of the blanks would be clamped between the clips and the walls. The spacing of the end blanks should be sufficient to permit the articles to be inserted in substantially flat condition. As shown in Figure 6 the space may be as much as 20% greater than the length of the final package.

After the blanks are properly positioned, sufficient articles are stacked between them to reach substantially to the top of the blanks, and the bag C is slipped over the trough 10 and its contents from the free end of the trough (see Figure 6). This operation is rendered possible by the provision of the slot 27 between the trough and the base 23 and is greatly facilitated by the lip 14. This lip projecting as it does beyond the side walls

11 and 12 engages the lower margin of the open mouth of the bag and serves to guide the bag as it is gradually drawn over the forward end of the trough. In this way it is rendered possible to 5 slip the bag into position without the exercise of great care or skill and without the danger of tearing the bag. It is to be noted in this connection that the upper front corners of the walls 11 and 12 are rounded off and the front ends of the walls 10 taper off into the horizontal lip.

The next step consists in pushing the blank A toward the front end of the trough. This operation moves the articles until they contact the blank B, thereafter further pressure on the blank 15 A moves the two blanks and the interposed articles toward the bottom of the bag and causes the legs of the blank B to be released from the blades 15 and 16. Then the entire assembly, bag and all, may be removed from the device and stood 20 up on the closed end of the bag. Finally the open end of the bag is closed and sealed in the manner previously described.

I am aware that packages have been proposed consisting of a frame completely enclosing the 25 articles to be packaged and the container, but my package and method of constructing the same are distinct therefrom in that I employ blanks for the supporting medium which do not completely surround the articles and which are thus 30 more economical in material and manufacture, easier to store and handle, and provide a simpler and more effective way of accomplishing the desired result.

The foregoing specification and description include the essential and distinctive thought of my 35 invention, but it is to be distinctly understood that the same may be modified in various ways and/or combined with various other details without affecting the peculiar results obtained and 40 without departing from the spirit of the invention or the scope of the appended claims, in which I intend to claim all the patentable novelty inherent in my invention.

I claim:—

45 1. A method of making a package from a pre-formed paper tube and two U-shaped blanks, consisting of the steps of placing the blanks on edge on a horizontal surface with their corresponding

legs in alinement and extending toward each other and leaving an open space between said legs, inserting the articles to be wrapped within the space between the two blanks, inserting the assembly of blanks and articles within the paper 5 tube and finally sealing the tube.

2. A method of making a package from a pre-formed paper bag and two U-shaped blanks, consisting of the steps of placing the blanks on edge on a horizontal surface with their corresponding 10 legs in alinement and extending toward each other and leaving an open space between said legs, inserting the articles to be wrapped within the space between the two blanks, slipping the open bag over the blanks from one end, pushing the 15 assembly of blanks and articles to the bottom of the bag and finally closing and sealing the open end of the bag.

3. A method of making a package from a wrapper and two U-shaped blanks, consisting of the 20 steps of placing the blanks on edge on a horizontal surface with their corresponding legs in alinement and extending toward each other and leaving an open space between said legs, inserting 25 the articles to be wrapped within the space between the two blanks and applying a wrapper about said assembly of blanks and articles.

4. A device for use in wrapping or packaging dry goods, said device consisting of a U-shaped trough, an adjustable stop secured near one end of said trough whereby a U-shaped blank may be positioned on its edge within the trough with its yoke against the stop and its legs extending toward the middle of the trough, and clamping means disposed at the other end of the trough to 30 hold a second U-shaped blank in opposite relation to the first blank.

5. A device as defined in claim 4, said clamping means consisting of a thin, sharp blade secured to each of the side walls of the trough 40 whereby the legs of the U-shaped blank may be impaled thereon.

6. A device as defined in claim 4, one end of said trough being secured to a raised support, the other end of the trough being free so that a bag 45 or tube may be slipped over the trough from the free end thereof.

ALFRED J. BROOKS.
